LUMINAIRE

Myron F. Pettengill, Marblehead, Mass., assignor
to General Electric Company, a corporation of
New York

Application May 25, 1953, Serial No. 25,181

Term of patent 14 years

(Cl. D48—31)

To all whom it may concern:

Be it known that I, Myron F. Pettengill, a citizen of the United States, residing at Marblehead, in the county of Essex, Commonwealth of Massachusetts, have invented a new, original, and ornamental Design for a Luminaire, of which the following is a specification, reference being had to the accompanying drawing, forming a part thereof, in which

Fig. 1 is a side elevational view of a luminaire, showing my new design;

Fig. 2 is a top plan view thereof; and

Fig. 3 is an elevational view looking at the right end of Figure 1.

I claim:

The ornamental design for a luminaire, as shown.
